UNITED STATES PATENT OFFICE.

RALPH W. GEARHART, OF JOHNSTOWN, PENNSYLVANIA.

APPARATUS FOR FILLING CARTONS.

Application filed October 5, 1921. Serial No. 505,463.

To all whom it may concern:

Be it known that I, RALPH W. GEARHART, a citizen of the United States, and residing in the city of Johnstown, in the county of Cambria and State of Pennsylvania, have invented or discovered the new, useful, and Improved Apparatus for Filling Cartons, of which the following is a specification.

My invention consists in new and improved apparatus for filling cartons with ice cream and other semiliquid frozen products.

In the present practice the paper cartons or containers are placed in turn under the spout of a freezer and the cartons filled with the semi-liquid product. The cartons are then placed on a table and the lids applied; and the cartons are then placed in the refrigerating compartment for the complete solidification of their contents.

There are a number of important objections to this method, as now practised. Thus, the cartons are repeatedly handled by the employees, thus becoming soiled and unattractive. The method is slow, thus being wasteful of time and labor. Again, the fitting of the lids on the filled cartons frequently results in denting in or partially collapsing the walls of the carton. The semi-frozen product usually overflows down the exterior wall of the cartons, staining the same.

The object which I have in view is the provision of apparatus for use in filling and lidding the cartons, the use of which will save time and labor, minimize the handling of the latter and which will enable the lids to be rapidly fitted into place without danger of distorting the walls of the cartons.

Generally speaking, my improved apparatus consists in the following.

I provide a new and improved filling box in which a plurality of unlidded cartons are placed, and which is pushed along a table, preferably provided with a roller surface, so that the cartons are brought in turn under a funnel member which is placed beneath the spout of the freezer, the arrangement being such that when a carton, or a pair of cartons, is filled the box is moved along the table to spot another carton or pair of cartons under the funnel, the excess product being scraped back into the unfilled cartons and prevented from overflowing down the outside of the carton. When the cartons contained in the filling box have all been filled, the box is removed and the

lids applied to the cartons, means being provided for supporting the walls of the cartons against distortion or collapse while the lids are being fitted in place. As fast as the boxes whose cartons have been filled are removed from the filling table, additional boxes loaded with empty cartons are slid onto the table, the filling operation being thus continuous. The lidded cartons are removed, from the box and placed in the refrigerating compartment for the hardening of their contents.

I show a new and improved filling table structure.

I show a new and improved filling funnel member.

I show a new and improved filling and lidding box for the cartons.

Other novel features of construction and arrangement of devices and parts will appear from the following description.

In the accompanying drawings, wherein is illustrated a convenient embodiment of the principles of my invention, Fig. 1 is a side elevation of the filling table showing a filling and lidding box thereon; Fig. 2 is an end view of the same; Fig. 3 is a top plan view of the same; Fig. 4 is an enlarged plan view of one of the filling and lidding boxes with the top lids closed; Fig. 5 is a side elevation of the same; Fig. 6 is a view similar to Fig. 4 with the top lids removed to show the lower lids or clamping boards. Fig. 7 is a reduced section taken along the line VII—VII in Fig. 5; Fig. 8 is a similar section with the top lids shown open, and Fig. 9 is an enlarged broken perspective showing the clamping boards.

The following is a detailed description of the drawings.

A represents the filling table whose frame is formed by the longitudinal side beams 1 connected together, preferably at their bottom edges by the cross braces 2, and supported at a convenient elevation by the legs 3. 4 represents a plurality of horizontally disposed rollers having their ends journaled in the side beams 1 below the top edges of the latter, thus forming a roller table surface, the side beams forming guides.

From each side beam a pair of spaced apart standards 5 extend upwardly, the said pairs being aligned transversely of the table, as shown in Figs. 2 and 3. Said standards are slotted downwardly from their tops, as shown at 6, to receive the bent ends of the

plates 7 attached to the opposite ends of the funnel block or member B which is provided with a downwardly contracting funnel opening 8. The funnel opening may be of sufficient size and shape to fill one or more cartons at one time, as may be desired. I have shown it of proper size to fill two cartons at once. The funnel block is positioned beneath the spout C of the ice cream freezer, said 10 spout being provided with a suitable hand valve or gate 9.

The lower face of the funnel block is horizontal and is recessed around the funnel opening to receive a rubber wiping mat 10 15 cemented or otherwise secured in place, and which surrounds the lower end of the funnel opening 8.

D represents one of the filling and lidding boxes in which the cartons are placed.

20 Said boxes are long, narrow and shallow, having permanent bottoms 11, sides 12 and ends 13. The end walls of said boxes are provided on the inside with horizontal cleats or brackets 14 spaced above the bottom of 25 the box for the adjustment of a false floor, so that cartons of different heights may be filled and lidded. The top of the box D is provided with a pair of lids 15, meeting along the central axis of the box and hinged 30 to the same along their longitudinal edges, as at 16. When closed the said lids 15 assume the positions shown in Fig. 7, and when open in the horizontally extended positions shown in Fig. 8, the edges of the lids 35 bear against the sides of the box, as shown in said Fig. 8.

The lids 15 are somewhat longer than the box, their extended ends acting as handles for lifting and carrying the boxes when the 40 lids are closed, spring catches 17 attached to the under side of the lids engaging lugs 18 on the ends of the boxes to hold the lids against accidental opening. The lids have their abutting edges recessed as at 19 to 45 form, when the lids are closed, openings through which the upper walls of the paper cartons extend when placed in the box, the tops of the cartons being flush with the tops of the lids when the latter are closed. Thus 50 the depth of the box may be such as to properly support cartons of a certain standard size, for instance a quart carton, on the floor of the box with the top of the carton flush with the top of the lid; while in case 55 cartons of less height, say pint cartons, are to be filled, a false floor would be placed on the cleats 14 to raise the top of the cartons flush with the lids.

In the drawings the openings in the top 60 lids, when the latter are closed, are shown as round, the box illustrated being especially designed for filling round cartons, but it will be understood that the shape of the opening should correspond to the contour of the 65 particular cartons to be filled. When closed

the lids 15 fit about the cartons and support the walls of the same.

20 and 21 represent a pair of horizontally disposed clamping plates supported in the box C beneath the lids 15. The ends of 70 said plates rest on horizontal cleats 22 affixed to the end walls of the box D above the cleats 14. The said plates are normally forced apart by means of the helical springs 23 whose ends are seated in sockets in the 75 abutting edges of the plates. The abutting edges of said plates are provided with recesses 24, which recesses, when the plates are forced together, fit snugly about the cartons, clamping them stationary. I prefer to knurl 80 or roughen the walls of the recesses 24, as shown in Fig. 9 to more firmly grip the cartons when the plates 20 and 21 are forced together. To properly hold the plates in alignment, I prefer to attach to the ends of 85 the plate 20 the guide members 25 between which the plate 21 will move toward or away from the plate 20.

26 represents pins fixed in the outer lateral edge of the plate 21 and protruding 90 through holes in the side wall of the box D, which pins when the top lids are opened up, as shown in Fig. 8, are engaged by the edge of one of the top lids 15 as shown in Fig. 8, thus forcing the plate 21 toward and into contact with the plate 20, as shown in Fig. 8. When the top lid 15 is raised out of contact with the pins 26, the springs 23 automatically force the plates apart, as shown in Figs. 6, 7 and 9, releasing the cartons. 100

Therefore, when the top lids are closed, the clamping plates are separated and the cartons are not clamped between the latter, but when the top lids are fully opened the plates 105 are clamped against the cartons and the latter are held firmly in position with their walls supported and braced, until the top lid in contact with the pins 26 is raised out of contact with said pins. Thus, I provide 110 one or more eccentric buttons 27 pivoted to the outer walls of the box D, which may be turned so as to engage and raise the top lid 115 sufficiently to partially elevate the top lid and thus permit the clamping plates to separate, thereby enabling the filled and lidded cartons to be lifted out of the filling box and deposited in the refrigerating compartment.

The operation of my invention is as follows. 120

A box D is filled with empty cartons, the latter being inserted down through the openings in the top lids, which are closed. The bottoms of the cartons rest on the permanent or false floor of the box D according to the 125 height of the cartons, and the top edges of the cartons being flush with the top surface of the top lids.

The loaded box is then placed on the roller surface of the table A and the cartons 130

in turn spotted under the funnel member B. In the illustration the funnel opening is of proper size and contour to include two adjacent cartons in a single filling operation.

5 The valve of the freezer spout is now opened and the semi-solid product flows down through the funnel opening 8. When the spotted cartons are filled, the box D is pushed along to spot the next two cartons in 10 the filling position, the rubber mat 10 wiping over the top surface of the moving box and forcing all excess product into the carton moving into the filling position.

When all the cartons in the box are filled, 15 the box is lifted off the discharge end of the table and placed on the lidding table. The top lids are now opened, thus forcing the plates 20 and 21 together, the filled cartons being now exposed to view but clamped between the plates 20 and 21 which engage the cartons a sufficient distance below their tops to permit the carton lids to be quickly applied, the support furnished by the clamping plates preventing the rapid application of 25 the lids from being accompanied by the distortion or crushing of the walls of the cartons.

The proper top lid 15 is now slightly raised from its open horizontal position, as 30 by turning the eccentric button 27, thereby releasing the pins 26 and permitting the plates 20 and 21 to spring apart thus releasing the now lidded cartons so that they may be lifted out of the box D and placed 35 in the refrigerating compartment. The top lids of the box A are again shut, the button 27 reversed and the box is ready to be re-loaded with a fresh supply of empty cartons. By feeding one box after another along the 40 table A, the end of the second box abutting against that of the box ahead, the filling operation may be made continuous and the ice cream may be allowed to flow in a continuous stream from the freezer spout, the 45 wiping mat on the lower face of the funnel member transferring the excess product into the next empty carton spotted in the filling position.

It is quite evident that by my method the 50 product may be discharged in a continuous flow from the freezer, and the filling of the cartons is very much speeded up. The cartons, moreover, are not soiled or crushed in the filling operation.

55 As it is a popular custom to serve ice cream and other frozen food products in small individual paper cartons, it is highly important to prevent the same becoming soiled, stained or distorted, and therefore the 60 use of my invention is very advantageous under these circumstances.

Although, for the sake of illustration, I have shown the filling boxes adapted for 65 operating with round cartons, it is perfectly evident that by altering the contour of the

apertures in the top lids and clamping plates, any character of carton may be used. Thus fancy shaped boxes may be used with equal facility.

Although, for the sake of clearness of illustration, I have described in detail the embodiment of the principles of my invention shown in the drawings, I do not wish to limit myself thereby, but claim broadly—

1. In mechanism for filling cartons with 70 ice-cream or other products, the combination of a support, a feeding funnel above said support, a filling box adapted to be slid along said support and to contain the cartons to be filled, and a closure for the top of 80 said box, said closure being provided with suitably shaped openings into which the top of said cartons extend substantially flush with the top surface of said closure whereby said cartons may by sliding said box along 85 said support be spotted for filling under said funnel, and said top closure being in sliding contact with the bottom of said funnel whereby the excess product fed to a carton will be scraped off and deposited in the succeeding cartons by the movement of 90 said box.

2. In mechanism for filling cartons with 95 ice-cream or other products, the combination of a support, a feeding funnel above said support, a filling-box adapted to be slid 100 along said support and to contain the cartons to be filled, a top closure for said box comprising a pair of coacting hinged lids, the adjacent edges of said lids being apertured to provide properly shaped openings 105 into which the tops of said cartons extend to substantially flush with the top surface of said lids whereby said cartons may by sliding said box along said support be spotted for filling under said funnel, and said lids 110 being in sliding contact with the bottom of said funnel whereby the excess product fed to a carton will be scraped off and deposited in the succeeding cartons by the movement of said box.

3. In mechanism for filling cartons with 115 ice-cream or other products, the combination of a filling box in which said cartons are placed, a closure for the top of said box, said closure being provided with suitably shaped 120 openings into which the upper portions of the cartons extend, and means within said box and adapted to clamp about said cartons to hold the same stationary for the application of the lids of the individual cartons when said closure is opened.

4. In mechanism for filling cartons with 125 ice-cream or other products, the combination of a filling box in which said cartons are placed, a pair of coacting top lids for said box, the adjacent edges of said lids being apertured to provide properly shaped openings into which the upper portions of the cartons extend, and means, operative when 130 said lids are opened, adapted to clamp about

said cartons to hold the same stationary and support the latter for the application of the lids of the individual cartons.

5. In mechanism for filling cartons with ice-cream or other products, the combination of a filling box in which the cartons are placed, a top closure for said box, said closure being provided with properly shaped openings into which the upper portions of the cartons extend, and means within said box, normally retracted, but adapted when said closure is opened, to clamp about said cartons to support the latter for the application of the lids of the individual cartons.

15 6. In mechanism for filling cartons with ice-cream or other products, the combination of a filling box in which the cartons are placed, a top closure for said box, said closure being provided with properly shaped 20 openings into which the upper portions of said cartons extend, and a pair of clamping plates below said closure and having their abutting edges recessed to form openings through which said cartons extend, means 25 whereby said plates are normally separated to permit the insertion of said cartons into the box, and means whereby said plates are forced together to grip said cartons when the closure is removed to permit the application 30 of the lids of the individual cartons.

7. In mechanism for filling cartons with ice-cream or other products, the combination of a filling box in which the cartons are placed, a pair of coacting top lids for said 35 box, said top lids having their abutting edges recessed to form properly shaped openings into which the upper portions of said cartons extend, a pair of clamping plates mounted in said box below said top lids, the abutting 40 edges of said plates being recessed to form openings through which the cartons extend, said plates being normally separated to permit the free insertion of the cartons into said box, and means whereby when said top 45 lids are extended into their opened position said plates are forced together thereby clamping about said cartons to support the latter for the application of the lids of the individual cartons.

50 8. In mechanism for filling cartons with ice-cream or other products, the combination with a table having a horizontally disposed top, a funnel member supported above said

table and provided with a vertically disposed funnel opening into which the product is discharged, and a filling box in which the cartons are placed, said filling box being provided with a closure having properly shaped openings into which the upper portions of the cartons extend to substantially flush with the top surface of said closure, said box being intended to be slid along said table to spot said cartons in turn under said funnel opening, the top surface of said closure being in sliding contact with the bottom of said funnel.

9. In mechanism for filling cartons with ice-cream or other products, the combination with a table having a horizontally disposed top, a funnel member supported above said 70 table and provided with a vertically disposed funnel opening into which the product is discharged, and a filling box in which the cartons are placed, said filling box being provided with a closure having properly shaped openings into which the upper portions of the cartons extend, said box being intended to be slid along said table to spot said cartons in turn under said funnel opening, the top surface of said box being in sliding contact with the bottom surface of said funnel member so that the surplus product 75 fed to one carton will be swept by the movement of said box into the next empty carton.

10. In mechanism for filling cartons with ice-cream or other products, the combination with a table having a horizontally disposed top, a funnel member supported above said 80 table and provided with a vertically disposed funnel opening into which the product is discharged, and a filling box in which the cartons are placed, said filling box being provided with a closure having properly shaped 85 openings into which the upper portions of the cartons extend, said box being intended to be slid along said table to spot said cartons in turn under said funnel opening, the bottom surface of said funnel member being provided with a flexible sweeping member 90 in contact with the top surface of the box 95 so that the movement of the box will sweep any surplus product fed to one carton into the next empty carton.

Signed at Johnstown, Pa., this 30th day of Sept., 1921.

RALPH W. GEARHART.
